UNITED STATES PATENT OFFICE

2,550,370

PRINTING INTERPRETER

John Mueller, Brooklyn, N. Y., assignor to Remington Rand Inc., Buffalo, N. Y., a corporation of Delaware

Application December 23, 1944, Serial No. 569,502

18 Claims. (Cl. 101—93)

1

This invention relates to a machine for interpreting the statistical data perforated in a card and printing the data on the same card in which it is punched, or on a separate card.

In the business use of statistical data two different types of punched cards are generally employed. The index data in one card is in the form of circular holes and in the other card in the form of slots. Different types of machines are necessary in the use of these differently perforated cards and the cards and the machines do not lend themselves to interchangeable use.

In some instances a user of the round hole type of card and the machines controlled thereby is called upon to prepare checks payable through certain banks that employ a check blank of the slotted card type. In order to print data on the faces of these checks from information contained in the round hole cards, both the round hole card and the slotted hole card must be put through a printing interpreter. This interpreter in one use is adapted for sensing the round hole card and then printing on the face thereof the data sensed therein. For the use contemplated by the present invention it is desirable to punch in the round hole card, the data perforated in the slotted card, so that the related round hole and slotted cards can be passed through the interpreter in sequence for sensing the data of the round hole card and printing it on the slotted hole card. Thus it is possible, by punching a card that can be sensed in one type of machine with data corresponding to the data in a card that can not be sensed in the same machine, to print the data on the card that can not be sensed. The well known ninety-column Powers data card provides a code of punched data wherein all the digits and a full alphabet may be accommodated.

A printing interpreter of the type described in Patent 2,311,471 issued to R. W. Ritzert on February 16, 1943, and the divisional application thereof and now Patent 2,426,951 issued September 2, 1947, is used for the purpose of interpreting the data punched in a Powers data card and then printing the data at selected positions on 45 the same card.

An object of the present invention is to apply to said printing interpreter a mechanism that can be adjusted to sense a leading Powers data card employing round data holes and to print or record legibly the data of said lead card on a following or trailing record card which may or may not be punched. Another object is to condition said mechanism so that instead of printing on the trailer or record card, the printing may be

2

done directly upon the lead or data card itself, when the data perforations of cards of this type alone, are to be interpreted and printed on the same card.

Another object of the invention is to position a lead data card, having data to be interpreted, so that the perforations can be sensed and to sequentially position a trailer record card that may have data punched therein that is not to be interpreted, so that said trailer card can not be sensed, means being also provided for rendering the trailer card positioning means ineffective.

Still further objects of the invention are to provide for the shift of a unit of the mechanism so that either the upper or the lower zone of the data card may be sensed; to automatically control the printing stops so that the printing on either a data or a record card may be located with respect to the zone of the data card from which the interpreted data has been sensed; and to disable the printing mechanism so that the lead or data card from which the data has been sensed, will not be printed upon when used in conjunction with a trailer or record card to be printed upon.

Other objects and structural features of the invention will be apparent from the following description when read in connection with the accompanying drawings, in which

Figs. 1 and 2 when combined, form a view in sectional elevation looking at the right hand side of the interpreter, showing the sensing and printing mechanisms;

Fig. 15 is a side view of the mechanism of Fig. 14 showing the operation of means for preventing shift of the interponents and controlling the card stops;

Fig. 16 is a view in perspective of the printing card stops and their control mechanism; and

Fig. 17 is a chart of the cycle of operation of the machine showing the relative functions of the main parts of the mechanism and the relation of the card movement with respect thereto.

The mechanism of the printing interpreter illustrated in Figs. 1 and 2 is, in its general organization, shown and described in the patent to Ritzert No. 2,311,471 of February 16, 1943; in Patent 2,426,951 issued September 2, 1947, forming a division thereof and in the Powers tabulator patents to Lasker, 2,044,119 of June 16, 1936, and 2,323,816 of July 6, 1943. Perforated cards are fed, one at a time, from a supply magazine 10 by a picker 11 and feed rolls 12 to an analyzing or sensing unit consisting of a lower sensing pin box 13 carrying sensing pins 14 and pin locking slides 15. The pin box is vertically reciprocated from a main shaft 16 so that the sensing pins 14 pass through the data index perforations of a card held in the card chamber 17 by a card stop 18 and cause the sensed data to be "set up" in an upper stationary pin box 19 provided with set pins 20, retract latch plates 21 and cam plates 22. The operations of the various parts are coordinated by suitable cams and fully described in the patents herein referred to.

As the data is "set up" in the upper pin box, the movements of the pins of the latter are transferred, through a removable connection box 23 (Fig. 14), to a decoding unit 24, whose stop bars 25 project to limit the upward travel of the printing wheel racks 26 that position the printing wheels 27 for printing impression on a card arrested therebeneath by an adjustable stop mechanism 28 and held by a clamp or pressure pad 29. The racks are released for rising movement under the influence of their springs 35, and restored by a vertically reciprocated rack bail 30.

After printing, the cards are passed by rolls 31 to an eject pocket 32. As one card is in the sensing chamber, the preceding card is in the printing chamber, the cyclic operation of the machine being substantially the same as disclosed in Patent 2,311,471, in which patent, each card is sensed and printed to provide a record thereon of the data that is punched therein. The present invention contemplates mechanism that may be selectively adjusted to carry out the functions of the machine covered by said patent and in addition make it possible, without altering the feeding sequence of the cards, to sense and print them alternately so that the data punched in the lead or data card of a pair may be printed

on the trailer or record card of said pair. To this end reference is made to Fig. 3 of Patent 2,323,816 wherein the card stop and pin retract mechanisms find their counterparts in Figs. 4 and 5 of the present disclosure, in which a stop cam 33 and a retract cam 34 are each mounted on the main shaft 16 together with a picker operating cam 36. The latter causes the feed of one card at a time from the magazine 10 to the sensing unit as fully explained in the patents referred to. The retract cam, near the completion of each rotation of the main shaft 16 momentarily lifts a roller lever 37 and a vertical push rod 38, the upper end of the latter of which raises one end of a lift or retract finger 39 loosely pivoted on a retract shaft 41 journalled in suitable brackets on the frame of the machine. Adjacent the lift finger 39, the retract shaft 41 has keyed thereto spaced retract arms 42 in the outer ends of which is journalled a retract control pawl shaft 43 carrying retract control pawls 44 and 45. Manually controlled retract pawl 45 is loosely pivoted on shaft 43 while the card controlled retract pawl 44 is fixed thereto, both pawls presenting (Fig. 7) toe portions 46 and shoulders 47, the latter of which engages a limit pin 48 secured in the adjacent arm 42. Pawl 45 has a pin and slot connection 50 in a vertical extension 49 thereof, with a pawl setting link 51 (Figs. 4, 5, and 7) which is notched as at 52 (Fig. 7) for adjustable relation with a slotted detent plate 53 mounted on the front face of the machine. The link is adjusted endwise by manipulation of the finger knob 54 against the resistance of a spring 55 (Fig. 13) to bring the toe 46 or pawl 45 over a lift lug 56 (Fig. 5) formed on top of the lift finger 39.

Heretofore, in the operation of the interpreter, the set-pin latch plates 21 were actuated in each cycle of machine operation by movement of the lift finger which was secured directly to and rocked the retract shaft 41 to cause unlatching movement of the plates 21. In the present instance, it is necessary that the machine also operate in like manner but, in addition, be conditioned by adjustment of the pawl setting link 51 to place control of the retract mechanism in the data card that is being sensed, so that the data set up in the upper pin box 19 can be retained while the trailer or record card of a pair of cards passes through the sensing mechanism. To this end, the card controlled retract pawl 44 fixed to shaft 43 is arranged alongside pawl 45 so that its toe 46 may be swung to a position over the lug 56 on lift finger 39 when shaft 43 is rocked at its opposite end by a retract link 57 (Figs. 4 and 7).

When the interpreter is to be used to sense a data card and then print the data punched therein directly on said data card, the pawl setting link 51 is pushed inwardly to throw the toe of pawl 45 over the lift lug 56 (Fig. 13) so that on each cycle of machine operation when the retract cam lifts push rod 38, the latter will, through finger 39 and pawl 45, raise the shaft 43 and, through the retract arms 42, rock the retract shaft 41.

When the data card itself is to control the retract mechanism (Fig. 7) the link 51 is released from plate 53 and moves outwardly, and a control arm 58 attached thereto and having a free end 59, is moved to withdraw said end from contact with the edge of the retract link 57 to permit the spring 61 to move the lower end of said link into operating relation with the pawl

shaft 43. The lower end of the link 57 is provided with a bayonet slot 62 in whose lateral shouldered extension 63 a pin 64 then seats to operatively join the link 57 with the pawl shaft 43 through an arm 65 secured to said shaft and on which arm said pin 64 is mounted. When the link 57 is pushed in to enable pawl 45 to cause the retract shaft 41 to be operated once in each cycle, as explained, the free end 59 of arm 58 pushes the lower end of link 57 to disengage the pin 64 from the lateral slot extension 63 and align it with the vertical portion of the slot so that vertical movement of link 57 will be ineffective to influence the pawl shaft 43. Thus, while a control hole will be used in the data card of a pair of data and record cards, upon the record card of which pair the information punched in said data card is to be printed, said control hole may be rendered ineffective as a controlling agent if the information punched in the data cards is to be printed on said data cards when the latter are passed through the machine without the record cards.

It is deemed desirable to describe the operation and control of the retract means before proceeding with a description of the coordinated action of the cards, the stop and the printing controls, which are conditioned by the pawl setting means. When a card is fed into the card chamber 17 (Fig. 2), which consists of a passage formed in the upper pin box 19 by spacing an upper pin plate 67 and a lower pin plate 68 (Figs. 10 and 4) through the medium of plate separators 69, the card is arrested in either a sensing or a non-sensing position by the card stop 18. The latter comprises a frame 71 carrying a stop strip 72 on which is mounted the spaced stop blocks 73. The frame 71 is movable vertically to bring the stop strip 72 into card stopping position so that the data index positions of a lead card will be in register with the sensing pins 14. The frame 71 (Fig. 11) is also movable to bring the stop blocks 73 into card arresting position so that the data index positions of a trailer card do not register with the sensing pins. Hence, a round hole card can abut the stop strip 72 to be sensed, but a slotted type card which cannot be sensed by round sensing pins will abut the stop blocks 73 and the solid zones of the card between the horizontal rows of data index positions will register with the sensing pins and damage to the slots will be prevented as the slotted type card passes through the card sensing chamber.

When the interpreter is operating to print the data on the same card from which it has been interpreted, Fig. 13, the adjusting link 51 is at its inwardly set position, the toe of pawl 45 overlies the lift lug 56 and the card controlled retract link 57 is held ineffective by arm 58. The card stop cam 33 on the main shaft 16 (Fig. 4), through a cam arm 76 pulls a stop link 77 down at about 194 degrees of each cycle of main shaft rotation. The upper end of the link 77 is slotted as at 78 (Figs. 5 and 13) to receive a pin 80 projecting from the end of a stop shaft arm 79, through the latter of which a stop shaft 81 is rocked and rocks, through an arm 82 and a link 83, stop frame actuating levers 84 to raise and lower the frame 71 in accordance with the degree of rocking movement given to the stop shaft. This degree of rocking movement is the same in each cycle of machine operation when the interpreter is sensing and printing the same card, but is varied in alternate cycles when a lead card is

to be sensed and the data thereof printed on a trailer card, adjustment for the latter of which is made by moving link 51 out to allow spring 81 to operatively associate link 57 with pawl shaft 43 through arm 65 (Figs. 5 and 7). When the lead card goes into the card chamber it is stopped against the stop strip 72 which is moved down to card arresting position by the stop link 77. The card is sensed and a control hole therein causes operation through one of the sensing pins 14 and a set pin 20, of a control pin 85 (Figs. 1 and 7) in the connection box 23 which rocks a control shaft 86 journalled in suitable brackets on the frame of the decoding unit 24 and carrying both the arm 87 which is engaged by the control pin, and the arm 88 which moves the link 57 vertically. The set pin 20 corresponding to the control hole of the card is not latched up due to the absence of a lower extrusion thereon for latching engagement with the adjacent retract latch plate 21 and the arm 87 is wide enough to be engaged by pin 85 in any adjusted position of a sliding frame, which will be hereinafter referred to in connection with the description of a card-stop-changing means shown in Figs. 3, 14, 15, and 16.

When the link 57 is pulled up by arm 88 it rocks shaft 43 counter-clockwise through pin 64 and arm 65, and positions the toe 46 of pawl 44 over the lug 56 of the lift or retract finger 39. At the same time (Figs. 5, 6, and 7), another arm 91 fixed to the shaft 43, operating through a slotted push link 92, rocks a hook lever 93, pivoted to an auxiliary frame 94, to push a hook link 96 to the left against the resistance of a spring 97 until a latch 98 pivoted at 99 to said link, rides over the edge of a keeper plate 101 far enough for a shouldered portion 102 of said latch 98 to have latching engagement with the plate under the influence of a spring 103. The movement of the hook link 96 tensions a hook spring 104. The latter connects the link 96 with a hook stud 105 protruding through a slot 106 in link 96 from a hook 107, which latter is pivotally suspended as at 108 from the stop shaft arm 79. When the control pin 85 operates, the stop link 77 is in its lowered position and the card stop 72 is closed, and when the spring 104 is tensioned, it causes the catch end 109 (Figs. 5 and 12) of the hook 107 to press against the inside of a vertical flange 111 formed at one side edge of a stop link extension 112, which is adjustably secured to the link 77 by the screws 113 and an eccentric adjusting stud 114.

When the link 77 rises to open the card stop and release the data or lead card, its vertical movement will be greater than the vertical movement of the hook due to the different radial distances they are connected to arm 79 from the center of the stop shaft 81, and flange 111 will ride off the catch end 109 of the hook 107 and the latter will immediately snap beneath the flange 111 under the influence of spring 104 (Figs. 8 and 12). When the next card, which is the trailer, comes into the card chamber it will be stopped in a different position than its predecessor because the stop closing drop of link 77 will, through extension 112, pull the hook 107 down a distance equal to the drop of said link and the shorter radius arm of the hook will rotate the stop shaft 81 a sufficiently increased amount to bring the card stop blocks 73 into card arresting position. When the hook 107 is pulled down it causes the pin 80 in shaft arm 79 (Fig. 8) to have a relatively greater movement downwardly than

the lowering movement of the link 77, which greater movement is permitted by the slot 78 in the link. The pin thus moves further down when the hook 107 pulls on arm 79 than when the link 77 pulls on the pin directly and this difference in downward movement of the pin 80 is sufficient to press down the ledge end 116 of latch 98 to disengage the shouldered portion 102 of the latch from its keeper plate 101, and allow the spring 97 to pull the hook link 96 to the right, a distance permitted by the length of the slot 106, to move the latch 98 to a free position atop plate 101 (Figs. 8 and 12). The extension 112, however, is engaging the hook 107 with sufficient pressure to prevent the hook link 96 from disengaging the hook 107 from plate 112 by its pull on the stud 105. When the stop link 77 starts to rise on its next stop opening movement (Figs. 9 and 12), the pressure of extension 112 on the hook 107 will be relieved and the hook link 96, under influence of spring 97, applying pressure to stud 105 through slot 106, will swing the hook from beneath the flange 111 of member 112, so that on the next downward stroke of stop link 77 the stop frame 71 will be given its short closing movement (Fig. 5) to place strip 72 in position to arrest the next lead or data card.

The auxiliary frame 94 (Figs. 6 and 7) is suitably secured to a part of the frame of the machine adjacent the left end of the card sensing mechanism and provides a bearing for the shafts 41, 43 and 81 as well as a support for the latch plate 101 and a spring plate 117 to which an end of spring 61 is attached. The frame 94 also has secured thereto a block 118 into which is threaded a stud screw 119 positioned beneath one of the retract arms 42 to provide an adjustable rest therefor. The frame of the machine supports a guide plate 115 (Fig. 4) through suitable slots in which pass the push rod 38, stop link 77 and hook 107.

The printing mechanism of the patent to Ritzert 2,311,471 is employed herein and varies in such details as are necessary to adapt the present invention thereto. A cam shaft 120 (Figs. 2 and 3) carrying a number of control cams including a printing wheel firing cam 121, a printing wheel restoring cam 122, a depressor cam 115 and a pressure pad cam 210, is driven in synchronism with the main shaft 16 through the worm gear and wheel combination shown in Fig. 13 of the Ritzert patent referred to and wherein the shafts 121 and 122 have their counterparts in the present shafts 16 and 120, respectively. Through suitable pitmans operated from the shaft 16 to raise and lower the rack bail 30 (Fig. 1), the racks 26 are permitted to rise under influence of their springs 35 to position the printing wheels 27 for printing, said racks being restored by downward movement of the bail. The racks straddle a fixed cross bar 123, beneath an end of which is disposed a print lockout pawl 124 (Figs. 3 and 7) pivoted with the upper end of a connecting rod 126, as at 127, to one arm of a bell crank 128. The other arm is connected by a restoring link 129 with a bail rocker 130, the restoring bail rod 131 of which moves out of the path of spring plunger operated firing fingers 135 which force the print wheels 27 with their support arms 132 down to effect printing action when said fingers are released by a firing bail 133. The firing bail is actuated through a release arm 134, bell crank 136, draw link 137, cam arm 138 and cam 121 while the restoring bail rod 131 which restores the printing wheels to

fully retracted position after printing occurs, is operated by a cam lever 140 connected to rod 126 and actuated by cam 122.

The bell crank 128 and lockout pawl 124 are connected by a spring 142 which tends to keep the upper end of the pawl 124 beneath the bar 123 so that, as rod 126 is permitted to rise by the low part of its controlling cam 122, it is prevented from having such full rising movement as would withdraw the bail 131 completely out of the path of the firing fingers 135. Hence, when the upper end of the print lockout pawl 124 is in position to engage the under side of bar 123, printing cannot occur.

When the machine is sensing a card, the cam plates 22 in the upper pin box will be displaced laterally by the engagement of the set pin extrusions 143 with cam openings 144 in said cam plates and movement of the latter will rock a bail arm 146 (Fig. 4) through bail 147 and shaft 148 to place a spring 149 under tension. The upper end of the arm 146 has a pin and slot connection 150 with a print control link 151, the pin being connected with one end of the link by the spring 149, the tension of which will yieldably push link 151 endwise, the latter being supported at one end on a parallel link 152 pivoted loosely on shaft 81 (Fig. 7). The end of the print control link 151 carries the oppositely projecting pins 155 and 156 which engage the depending ends 157 and 158 of the print control arm 159 and lockout pawl 124, respectively. The endwise pressure of link 151 acting on the print lockout pawl 124, through pin 156, will swing the pawl from beneath bar 123 and hold it so, as long as the cam plates 22 are in displaced position, so that printing can occur on the cards, successively.

When the adjusting link 51, however, is adjusted preparatory to sensing lead data cards and printing the data thereof on trailer record cards it becomes necessary to control the printing so that it will occur only on the trailer cards. This is accomplished through the medium of a non-print link 161 (Fig. 7) pivotally connecting the upper end of the hook lever 93 with a rock arm 162 secured to a sleeve rock shaft 163 to which is fixed the print control arm 159.

When sensing of the lead card occurs (Fig. 5) the hook lever 93 is latched in its swung position, through hook link 96, by the latch 98. The hook lever 93 has pulled on non-print link 161 to rock the sleeve shaft 163 through rock arm 162, and also the print control arm 159 so that the latter will restrain print control link 151 from having endwise movement and the print lockout function of pawl 124 will be maintained by spring 142 until the hook link 96 has its full release movement. When the lead card is sensed, spring 149 (Fig. 4) is placed under tension as previously described, but the positive action of the control arm 159 in engagement with pin 155 will negative the movement of the control link 151 that was momentarily caused by the displacement of the cam plates 22 acting on arm 146. When the lead card passes into the printing chamber the trailer card comes into the sensing chamber (Fig. 8) and when the card stop block 73 is fully down the latch 98 is released by pin 80 and permits a slight release movement of hook link 96, under influence of spring 97, but not enough to rock hook lever 93 to cause the lockout pawl 124 to be completely forced from beneath bar 123. However, when the stop link 77 starts to rise to open the stop and let the trailer card pass into the printing chamber, the

stop link extension 112 will relieve the pressure on hook 107, and the latter will allow the spring 97 to pull hook link 96 to its limit (Fig. 9). Hook lever 83 will thus be given a full throw and through link 161 will rock the print control arm 159 out of the way of pin 155 so that spring 149 will cause the pin 156 on print control link 151 to swing the lockout pawl 124 so that its upper end moves from beneath bar 123 (Fig. 3). Therefore, when the connecting rod 126 rises it can have a full stroke which will rock bail 131 entirely out of the way of the printing wheel firing fingers 135 so that printing occurs on the trailer card when the firing bail 133 is released. When the trailer card passes through the sensing means, it is not sensed (Fig. 11) and the pin set-up from the preceding lead card is retained because the control pin 85 (Fig. 7) is not operated to swing control pawl 44 into position to cause retract, and through the cam plates 22 and bail arm 148 the tension on spring 142 (Fig. 4) is maintained. When the lead card of the next pair of cards is sensed, the print control arm 159 through the action of control pin 85 is again moved to restrain print control link 151 and allow spring 142 to keep the print lockout pawl 124 in place beneath the bar 123, so that rod 126 cannot have a full rising movement and the lead card will not be printed upon when it passes through the printing chamber.

When the adjusting link 51 is pushed in, the timed relation of the operating parts of the mechanism is substantially the same as shown in the timing diagrams of Figs. 29 and 30 of the Ritzert Patent 2,311,471. When the link 51 is moved out, the timed operating relation of the parts of the machine is as shown in Fig. 17 of the drawings herein and, as in the Ritzert patent, the beginning of a cycle of operation finds the fully raised sensing pins ready to start down and the sensing mechanism card stop closed (Fig. 4). The lead or data cards and the trailer or record cards, relatively indicated in outline on the time chart are arranged in the magazine 10 in alternate sequence and at 30 degrees of main shaft rotation, a lead card is engaged by the picker and advanced by the feed rolls to the card chamber to engage the data card stop 72 which closes at about 200 degrees, the card stop link 77 having completed the first downward movement of its two stroke cycle. The lead card is sensed at about 240 degrees and the control pin 85 causes shift of the hook link 96 to its latched position and simultaneous movement of print control arm 159 to assure movement of lock out pawl 124 beneath the bar 123 under tension of spring 142. The card controlled pawl 44 transmits movement to the retract shaft 41 at about 347 degrees but the continued rise of the sensing pins results in the new set-up of the set pins which are fully latched up at 358°. At this time the permutation plates are in decoding position. At 30 degrees of the next cycle the trailer card is engaged by the picker for feeding, the sensing pins are going down and the control pin is dropped and control pawl 44 (Fig. 7) is released from retract position and is aligned with pawl 45 (Fig. 5) at about 65 degrees. At about the same time, the printing racks 26 and bail 30 are completely down and the stop bars 25 of the decoding unit are moving out to stop the racks in their upward movement which is permitted by the rising movement of the bail 30 which starts at about 65 degrees. The card stop 72 opens and releases the lead card at 125 degrees and at this time the hook 107 will snap

75

beneath the extension plate 112 of stop link 77. At about 165 degrees the card stops in the printing chamber (Fig. 3) rise to arrest the lead card at about 220 degrees and detain it until it is engaged by the clamp 29 at 234 degrees and held beneath the printing wheels 27. The card stop in the sensing chamber has closed from 194 to 212 degrees and through movement of the hook 107, the stop shaft arm 79 and its pin 80 have their maximum movement to cause stop blocks 73 (Fig. 8) to arrest the trailer card at about 229 degrees in non-sensing position, and the pin 80 partially releases hook arm 96 through the latch 88. No sensing can occur and the pin set-up is not disturbed. The control pin 85 and pawl 44 are not moved and the push rod 38 lifts the finger 39 without operating the retract shaft 41. Operation of the printing control bails 131 and 133 occurs between 220 and 250 degrees but printing on the lead card which would normally occur at about 245 degrees, is prevented by the lockout pawl 124 which bars full release movement of bail 131. The lead card is released by a pressure pad at about 262 degrees and leaves the printing chamber and is deposited in the eject pocket 32. The trailer card is held in the sensing chamber until the card stop opens in the following cycle at 132 degrees. The opening of the stop (Fig. 9) releases the hook 107 and hook link 96 has a full movement under influence of its spring 97 and swings print control arm 159 away from pin 155 so that pin 156 of print control link 151 can swing the upper end of the print lockout pawl 124 from beneath bar 123 against the resistance of spring 142. A new lead card comes into the sensing chamber, after the preceding trailer card leaves at about 192 degrees, and is detained against stop 72 for sensing. The trailer card is detained in the printing chamber and clamped for printing which occurs at 245 degrees. In the rest of the cycle the sensing of the new lead card retracts the set-up of the preceding lead card and the operation of the control pin 85 again conditions the mechanism to prevent printing on the lead card, prevent sensing of the trailer card and permit printing on said trailer card. At the end of the run of cards, a last card is used which will have only a control hole so that retract will occur and the machine will be cleared. In one cycle, the lead card is sensed and the trailer is printed upon and in the next cycle, the trailer card passes through the sensing chamber but is not sensed and the lead card passes through the printing chamber and is not printed upon.

The printing chamber card stops, pressure pad and controls therefor illustrated in Figs. 7, 14, 27, 28, and 31 of Ritzert Patent 2,311,471 are employed in the present machine with but slight variation and find their counterparts in the present Figs. 3, 14, 15, and 16. The printing chamber 164 presents a card supporting platen 165 having seven slots in which only two card stops 166 and 167 are shown in this particular instance. The stops are elevated in accordance with the zone of the card being sensed and halt the card for printing, at two different places by engagement with the leading edge thereof. Stop 166 will arrest the card so that printing of the data in the upper zone of the card will occur close to the top edge of the card and stop 167 will arrest the card so that printing of the data of the lower zone will take place adjacent said lower zone. The control of stop selection is through the adjustment of a sliding frame 168 (see Fig. 14) which shifts the interponents 169

11

of the connection box 23 to transfer the motion of the set-up pins 20 corresponding to the upper and lower zones of the card data to the decoding unit 24. Movement of the bell crank and handle combination 170 pivoted to box 23 shifts frame 168 relatively to said box and raises or lowers a vertical plate 171. The plate, at its lower end, carries a stud 172 and an ear 173 to the latter of which is pivoted a lever 174 secured to a pivoted sleeve 175 to which is also attached an arm 176. When the data of the upper zone of the cards has been printed in one run, the handle 170 is moved to simultaneously shift the slide frame 168 for printing the data of the lower zone of the cards, on a rerun, and to select the corresponding stop in the print chamber by actuation of a cross shaft 177 through the medium of said arm 176, a link 178, and an arm 179. The shaft 177 carries a stop arm 181 whose pin and slot connection to a key link 182 permits adjustment of the latter to align notches 183 therein with either stop 166 or 167 depending upon the position of the frame 168. The stops are retracted by a depressor arm 184 operated through a shaft 186 and cam lever combination 187 from a stop cam 188 (Figs. 2 and 3) on the shaft 120 in proper timed relation with the mechanism as shown in the cycle chart of Fig. 17, and any shifting of the key link 182 (Fig. 16) can occur when the stops are depressed and only when the sensing chamber is devoid of a card. This is so that injury to the interponent pins by a shift of the frame 168 is guarded against, when the sensing and interponent pins are raised, and to this end a locking means is embodied in the mechanism to prevent zone shifting except at the end of a run of cards. The stud 172 on plate 171 is engaged by a hook 189 when the machine is running because the pin 191, of a sleeved arm 192 connected to said hook 189, is resting atop a lever 193 which is moved to the position shown in Fig. 15 by the action of a no-card pin 194 (Fig. 14) and a series of linkages working in conjunction with the standard start-stop mechanism commonly employed in Powers tabulators and found in the Ritzert patent referred to herein as well as in the Powers Patent 2,044,119. The main shaft 16 carries a cam 196 for raising a vertical bar 197 to release the hook 189 through lever 193 when the sensing chamber is devoid of a card, so that the frame 168 can be shifted to select the zone of the card from which the perforated data is to be printed without damaging the interponents 169.

The printing of the data characters for the upper zone is done near the top edge of the card and as stop 116 in raised position might interfere with the type wheels, a pressure pad 29 is employed to mechanically clamp the card to the printing platen 165 before the stop is withdrawn preparatory to printing. The pressure pad, Figs. 2 and 3, comprises a float bar 199 extending across the platen between the support arms 201 and having suitable bosses on its underside for card holding engagement. Each end of the bar beyond the edge of the platen carries a stud 202 which is engaged by a plunger 203 forced upwardly against the action of a spring 204 when the roller of a cam lever 205 rides in the depression of a cam 210 on shaft 120. Downward pressure on each plunger by stud 202 is maintained by a spring 206 connecting the end of each support arm 201 with the adjacent wall of the print unit frame 207, so that when the plunger at each side of the platen lowers under

12

the influence of cam 210, the springs 206, that connect the arms 201 to the frame, will cause said arms 201 to drop down about their pivotal points 209 to cause the pad to engage and hold the card, at which time the arms 208 pivoted to 201 at 209, also drop. These arms 208, carry the printing ribbon guides 211.

A mechanism, Fig. 3, is employed for engaging each of the printing wheel racks 26 and includes a pawl 212 for each rack, supported within guide combs 213 carried on the bar 214 whose arms 215 are secured to a suitable rock shaft 216. The latter is rocked by a depressor link 217 and bell crank lever 218 under influence of a depressor cam 115 on the shaft 120. The depressor mechanism provides a convenient and accurate means for aligning the type wheels 27 by counteracting lost motion between the parts and it also lowers or depresses the racks slightly and permits the withdrawal of the stop bars 25 without friction or jamming.

While I have described what I consider to be a desirable embodiment of my invention, it is obvious that changes in form could be made therein without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In a card interpreting and printing machine, means for feeding alternately arranged data and record cards, means for interpreting perforations in the data cards including a movable control pin, means for printing on the cards the data represented by said perforations, and means controlled by the movement of said control pin for preventing operation of the means for printing on the data cards.

2. In a card interpreting and printing machine, means for feeding alternately arranged perforated data and record cards, means for sensing perforations in the data cards, movable stop means for holding the data cards so that the perforations thereof are in register with said sensing means, means for printing on the succeeding record cards the data represented by said perforations, and means controlled by the data cards for adjusting the movement of the stop means for holding the record cards so that the perforations thereof are out of register with said sensing means.

3. In a card interpreting and printing machine, means for feeding alternately arranged perforated data and record cards, means for reading perforations in a leading data card, means for printing on the following record card the data represented by the perforations in said leading data card, means for preventing the printing means from printing on the data card, means for preventing the sensing of the perforations of said record card, and control pin means influenced by a perforation in the data card for controlling the operation of said printing and sensing preventing means.

4. In card printing apparatus, means for successively feeding cards, means for sensing data in alternate cards, control pin means operated by said sensing means, means for printing the sensed data of said alternate cards on the cards intermediate said alternate cards, and means actuated by said control pin means for auto-

matically disabling the printing means to prevent printing on said alternate cards.

5. In a record controlled machine, record sensing means including data set-up pins, latches for retaining said pins in set-up position, retract means for unlatching said pins, an actuating member operable in each cycle of machine action, means for operatively connecting said retract means and said actuating member, and means for adjusting said connecting means for controlling the operation of said retract means.

6. In a record controlled machine, record sensing means including data set-up pins, latches for retaining said pins in set-up position, retract means for unlatching said pins, an actuating member operable in each cycle of machine action, means for operatively connecting said retract means and said actuating member, and record controlled means for adjusting said connecting means to vary the operation of said retract means.

7. In a record controlled machine, record sensing means including data set-up pins, latches for retaining said pins in set-up position, retract means for unlatching said pins, an actuating member operable in each cycle of machine action, means for operatively connecting said retract means and said actuating member, record controlled means for adjusting said connecting means to vary the operation of said retract means, and means for manually adjusting said connecting means to provide unvarying operation of said retract means.

8. In a record controlled machine, record sensing means including data set-up pins, latches for retaining said pins in set-up position, retract means for unlatching said pins, an actuating member operable in each cycle of machine action, means for operatively connecting said retract means and said actuating member, record controlled means for adjusting said connecting means to vary the operation of said retract means, means for manually adjusting said connecting means to provide unvarying operation of said retract means, and means operable by the manual adjusting means for disabling said record controlled means.

9. In a record interpreting machine, record sensing means, record printing means, means for disabling the printing means, a stop for arresting a record in the sensing means, means for moving the stop to hold a record in one position at which it may be sensed, means for conditioning the stop moving means to enable the stop to hold a record in another position at which it cannot be sensed, and means controlled by the record for operating the stop conditioning means and said print disabling means.

10. In a record interpreting machine, record sensing means, record printing means, means for disabling the printing means, a stop for arresting records in the sensing means, means for moving the stop to hold a first record in one position at which it may be sensed, means for transferring the sensed record to said printing means, means for conditioning the stop moving means to enable the stop to hold a second record in a different position at which it cannot be sensed, and means controlled by the first record for operating the stop conditioning means and the print disabling means for preventing the sensing of said second record and the printing of said first record.

11. In a record interpreting machine, record sensing means, record printing means, means for

disabling the printing means, a stop for arresting records in the sensing means, means for moving the stop to hold a record in one position at which it may be sensed, means for transferring the sensed record to said printing means, means for conditioning the stop moving means to enable the stop to hold another record in a different position at which it cannot be sensed, and record controlled means for operating the stop conditioning means and the print disabling means for preventing the sensing of one record and the printing of another record.

12. In a record controlled machine having record sensing means including data set-up pins and means for releasably retaining the pins in set up position, an actuating member operable in each cycle of machine action, means operable in response to operation of said actuating member for actuating the second named means to release said pins, and means for adjusting the third named means for controlling the operation thereof.

13. In a record controlled machine having record sensing means including data set-up pins and means for releasably retaining the pins in set up position, an actuating member operable in each cycle of machine action, means operable in response to operation of said actuating member for actuating the second named means to release said pins, and record controlled means for adjusting the third named means for controlling the operation thereof.

14. In a record controlled machine having record sensing means including data set-up pins and means for releasably retaining the pins in set up position, an actuating member operable in each cycle of machine action, means operable in response to operation of said actuating member for actuating the second named means to release said pins, and record controlled means for adjusting the third named means for controlling one manner of operation thereof, and means for manually adjusting said third named means for arranging the latter for another manner of operation thereof.

15. In a record controlled machine having record sensing means including data set-up pins and means for releasably retaining the pins in set up position, an actuating member operable in each cycle of machine action, means operable in response to operation of said actuating member for actuating the second named means to release said pins, and record controlled means for adjusting the third named means for controlling one manner of operation thereof, means for manually adjusting said third named means for arranging the latter for another manner of operation thereof, and means operable by the manual adjusting means for disabling the record controlled means.

16. In a record controlled machine, record sensing means, a stop for arresting records at different positions in the sensing means, means for moving the stop including a pivoted arm and a link connected to the arm for moving the latter a predetermined arcuate distance to cause the stop to arrest records at one position, a hook on said arm and means on said link engageable by the hook for moving said arm a different arcuate distance to cause the stop to arrest records at another position.

17. In a record controlled machine as set forth in claim 16 including latching means for engaging the hook with said link means, and record

controlled means for actuating said latching means.

18. In a record controlled machine as set forth in claim 16 including latching means for engaging the hook with said link means, record controlled means for actuating said latch means, and manually controlled means for disabling said record controlled means.

JOHN MUELLER.
